DESIGN FOR A LACE

Jean Dognin, New York, N. Y.

Application July 11, 1936, Serial No. 63,782

Term of patent 3½ years

To all whom it may concern:

Be it known that I, Jean Dognin, a citizen of the Republic of France, residing in city of New York, county and State of New York, have invented a new, original, and ornamental Design for a Lace, of which the following is a specification, reference being had to the accompanying drawing, forming part thereof.

The figure of the drawing is a plan view of a lace embodying my new design.

The design unit is contained between the dot and dash lines, which unit is repeated in regular succession as indicated by the extensions beyond the unit boundaries.

I claim:

The ornamental design for a lace substantially as shown and described.

JEAN DOGNIN.
